GRINDING WHEEL DRESSER

Frank A. Miller, Troy, N. Y.

Application September 11, 1947, Serial No. 773,410

4 Claims. (Cl. 125—11)

(Granted under the act of March 3, 1883, as
amended April 30, 1928; 370 O. G. 757)

1

The invention described in the following specification and claims may be manufactured and used by or for the Government for governmental purposes without the payment to me of any royalty thereon.

This invention relates to a grinding wheel dresser for attachment to a machine such as a thread grinding machine for dressing the grinding wheel to correspond to a highly accurate template.

In the production of hobs or other similar articles of manufacture on a thread grinding machine, the grinding wheel utilized in such machines must have an accurately shaped contour or cutting edge in order to produce the correct contour on the hob or other article. In the past, much difficulty has been encountered in producing the contour desired on the grinding wheel to the exacting requirements necessary for production of high quality hobs. The prior art devices utilized for such purpose were somewhat cumbersome and slow of use and the results obtained therefrom were of doubtful accuracy.

Accordingly it is an object of this invention to provide a device adapted to be readily secured to a machine for accurately and quickly dressing a grinding wheel to the contour desired.

Another object of this invention is to provide a grinding wheel dresser for a machine which can be utilized to accurately dress a grinding wheel to a desired contour by simple manipulation of single operating lever.

Another object of this invention is to provide a device for dressing a grinding wheel having adjustable resilient means for follower control.

The specific nature of this invention as well as other objects and advantages thereof will clearly appear from a description of a preferred embodiment as shown in the accompanying drawings in which:

Fig. 1 is a side elevational view of the grinding wheel dresser.

Fig. 2 is a detail view of the cylindrical bar member.

Fig. 3 is a detail view of the disks utilized to support the cutting diamonds.

Fig. 4 is a top view of Fig. 1 with the cover plate partially broken away.

Fig. 5 is an end view of the tool holder showing the manner of securing the cutting diamonds.

Fig. 6 is an enlarged fragmentary detail view showing the form of the template.

Fig. 7 is an enlarged side elevational detail view of the pin utilized to connect the actuating arm to the bar member.

2

Fig. 8 is a side elevational view of another connecting pin utilized with the pin shown in Fig. 7 for a similar purpose.

Fig. 9 is a detail perspective view of the spring guide member.

Fig. 10 is a detail view taken along the line 10—10 of Fig. 13.

Fig. 11 is a detail top view of the guide member.

10 Fig. 12 is a side elevational view of the roller bearing support pin.

Fig. 13 is a view similar to Fig. 1 shown partly broken away to illustrate the mechanism contained therein but with the base member removed.

15 Fig. 14 is a detail view of the pin on which the block slides.

Fig. 15 is a front elevational view of the block member.

20 This invention comprises essentially a tool holder mounted on a bar which is arranged for what may be called pantographical movement, the control of such movement being governed by a template. Spring means is provided to maintain a guide member against the template and a lever, which is indirectly secured to the bar, provides the means for moving the tool holder. The grinding wheel dresser is mounted on a suitable base which is adapted to be secured to a machine having a grinding wheel to be dressed.

25 In Fig. 1 there is shown in assembled relation a grinding wheel dresser embodying this invention. The elements of such dresser are mounted on a bracket 10 which has a substantially flat base portion 11. On one end of base portion 11 there is provided a pair of oppositely disposed upstanding arm-like members 12 and 13. Near the top of arms 12 and 13 there is provided a horizontally disposed hole 14. On the opposite 30 end of base portion 11 there is provided a pair of upstanding arms 15 and 16, which are substantially rectangular in shape. A horizontally disposed transverse hole 17 is provided in each arm 15 and 16 near the lower end thereof.

35 Bracket 10 is pivotally mounted to a base member 18 by a pin 19. Base member 18 is provided with an upstanding arm 20 having a transverse hole 21 therethrough near the top of such arm. Hole 21 accommodates pin 19 to secure bracket 10 to base member 18. Base 18 has a rearwardly projecting bracket-like member 22 having a rectangular portion 23 in which is provided a threaded hole 24 longitudinally disposed with respect to base 18. The bottom of base 18 has a dovetail 40 portion 25 and such portion along with threaded

hole 24 are utilized to mount the grinding wheel dresser to a thread grinding machine or other machine which can advantageously utilize this invention.

Hole 17 and vertically disposed arms 15 and 16 are provided to support a shaft 26 and shaft 26 in turn slidably supports a block member 27. Block 27 comprises a cylindrical portion 28 having an axial longitudinal hole 29 to accommodate shaft 26. On top of cylindrical portion 28 there is provided an integrally formed transversely disposed rectangular top portion 30. Such member has a hole 31 extending therethrough at right angles to hole 29. Longitudinally disposed, diametrically opposed slots 32 are provided in top portion 30 symmetrical with respect to the vertical axis of cylindrical portion 28. A vertically disposed hole 33 is provided in top portion 30 which is disposed on the vertical axis of cylindrical portion 28. Slots 32 and hole 33 are provided for a purpose to appear later. On opposite sides of top portion 30 there is milled a rectangular recess 35. Each of these recesses is provided to support a ball bearing as will be later described.

Hole 31 in top portion 30 accommodates a cylindrical bar member 34. On one end of bar member 34 there is provided an integral square head portion 36. A transverse hole 37 is provided in such head. In the opposite end of bar 34 there is provided another transverse hole 38, the axis of which lays in the same plane as hole 37. A rectangular, longitudinally disposed keyway 39 is provided in bar 34 intersecting the hole 38. In approximately the center of bar 34 there is provided a transverse hole 40 which is disposed at right angles to the axis of holes 37 and 38.

When bar 34 is inserted in hole 31 and hole 40 aligned with slots 32, a pin 41 is inserted in hole 40 through slot 32. Pin 41 is of such length that a sufficient amount projects from each side of top portion 30 in order that a ball bearing 42 may be mounted thereon. Each of the ball bearings 42 rest within respective recesses 35. On top of portion 30 there is rotatably supported a ball bearing 43 on a vertically disposed pin 44 which is press-fitted into hole 33.

A plate 45 is secured to the top of upstanding arms 15 and 16 of bracket 10 by means of screws 46 and dowel pins 47. A rectangular cut-out portion 48 is provided in the center of such plate and ball bearing 43 contacts surface 49 of such cutout. A plate 50 is similarly secured on top of arms 15 and 16 adjacent plate 45 by means of vertically disposed screws 51 and dowel pins 52. The edge of plate 50 adjoining plate 45 provides the other bearing surface for ball bearing 43. Thus as block 27 is moved along shaft 26, ball bearing 43 provides a relatively frictionless bearing support.

Slightly to the right of plate 45, as shown in Fig. 4, there is also mounted a template 53. Such template comprises a rectangular bar-like member having a centrally disposed projection 54 thereon facing to the right, as shown in Fig. 6. Template 53 is secured to arms 15 and 16 by screws 55. Projection 54 of template 53 is shaped to conform to the contour desired to be produced on the grinding wheel of the machine to which this fixture is to be attached. In the preferred application of this invention, the projection 54 takes the shape of a tooth on a threading hob as shown in Fig. 6.

A cover plate 56 is placed over plates 45, 50

and template 53. Such plate has a raised boss 57 in the center near the right-hand edge thereof and a vertically disposed hole 58 is provided through such boss and plate 56 in which is inserted a pin 59. Such pin is secured within hole 58 by a press fit.

An actuating arm 60 is pivotally mounted on pin 59 for actuation of bar 34, as will be later explained. A thumb screw 123 threaded into the end of pin 59 secures arm 60 to such pin. A vertically disposed hole 61 in arm 60 accommodates pin 59. Arm 60 comprises essentially a rectangular bar having one end 62 disposed at an acute angle with respect to the body thereof. A handle portion 63 is secured, preferably by welding, to bent end 62 and such handle is disposed upwardly, as shown in Fig. 1, to facilitate manipulation thereof. A portion of the other end 64 of arm 60 is cylindrical and a cylindrical bore 65 is provided in arm 60 from end 64 which extends a substantial distance into such arm, and the entering end of such bore is provided with internal threads 67. A rectangular recess 66 having rounded ends communicates with bore 65 from the underside of arm 60.

Connection between arm 60 and bar 34 is made principally by two pins 68 and 69. Pin 69 comprises two cylindrical portions 70 and 71 separated by an integral washer-like member 72.

The lower end of cylindrical portion 70 has a rectangular notch 73 and such end is inserted in hole 38 of bar 34. A key 74 inserted in keyway 39 likewise engages notch 73 thereby locking pin 69 against turning in bar 34. A screw 75 threaded

into a hole 124 secures pin 68 to bar 34.

A guide member 76 is placed on the cylindrical portion 71 of pin 69. Guide member 76 is substantially a rectangular member having a rounded end 77. A vertically disposed hole 78 in such guide member accommodates portion 71 of pin 69. Corners 79 and 80 of guide member 76 are preferably tipped with carbide to better resist wear. A vertically disposed rectangular notch 81 is provided in the rounded end 77 for a purpose to appear later.

Pin 68 is provided with a cylindrical collar-like integral bearing member 82. On the underside of such collar-like member there is integrally formed an axial threaded stud-like member 83.

Such stud-like member engages a threaded recess 84 provided on the top of pin 69. Collar-like member 82 thus secures guide 76. Upper end 85 of pin 68 is of slightly reduced diameter and intermediate such end portion 71 and collar-like member 82 a roller bearing 86 is placed thereon. Roller bearing 86 contacts the side walls of recess 66 provided in arm 60.

A spring guide member 87 comprising a block portion 88 having a vertically disposed hole 89 therein has a rearwardly facing stud 90, hole 89 in such block accommodating end 85 of pin 68. Stud 90 mounts one end of a spring 91 which is inserted in bore 65 of arm 60. A screw 92 turned into threaded end 67 of arm 60 retains a ball 128 which seats spring 91 within bore 65.

Guide member 76 is keyed to pin 69 by a key 93. Key 93 engages a suitable rectangular notch 94 provided in the washer-like member 72 of pin 69. Such key is secured to guide 76 by a screw 95. Thus guide member 76 is prevented from rotating on pin 69 and connection between arm 60 and bar 34 is attained.

A tool holder 96 essentially comprising a rectangular bar 97 is secured to the outer end of bar 34. Tool holder 96 is provided with a cylind-

drical ends 98 and 99 and end 98 is inserted into hole 37 of bar 34 and is positioned therein by a screw 100 which is screwed into a threaded cylindrical recess 101 provided in the end of cylindrical end 98. Tool holder 96 is locked by a set screw 129. Tool holder 96 is prevented from turning in hole 37 by keys 102. Keys 102 are placed in a keyway 125 provided in the end 98 of bar 97 of tool holder 96.

The holder for securing the cutting diamonds 104 and 105. Disc 104 is provided with two radially disposed rectangular grooves 106 and 107 disposed at somewhat less than 90 degrees. Disc 105 is provided with corresponding grooves 126 and 127 which are however of V shape. A rectangular vertically disposed notch 108 is provided in each of such discs which are engaged by key 130, which lies in a keyway 103 of bar 97 to lock such discs to bar 97. Tool bits 109 and 109' are respectively inserted in grooves 106 and 107 and each of such tool bits preferably has a diamond 110 in the point thereof. Bits 109 and 109' are secured within their respective grooves by a plurality of screws 111 which secure disc 105 to disc 104. A screw 112 having a knurled cylindrical head portion 113 is threaded into a hole 114 in cylindrical end 99 of holder 96 to secure discs 104 and 105 to holder 96 and to permit rapid removal thereof for resetting or replacement of tool bits 109 and 109'.

To dress a grinding wheel of a threading machine (not shown) the grinding wheel dresser is mounted on the machine by means of the dovetail 25 of base member 18. Guide member 76 is maintained against projection 54 of template 53 by the action of spring 91 bearing against pin 68. When handle or lever 63 of arm 60 is rotated about pin 59 in either a clockwise or counterclockwise direction, arm 60 is forced to pivot about pin 59, thus forcing block member 27 to slide on shaft 26 in a corresponding direction. This forces guide member 76 to slide along projection 54. As has been mentioned, projection 54 is shaped to correspond to a tooth being produced on a threading hob. Depending upon the direction of rotation of lever 63, the corners 79 or 80 will follow the contour of projection 54 of template 53. For example, when lever 63 is rotated in a clockwise direction, block 27 will be forced to move downwardly as shown in Fig. 4 and corner 80 of guide 76 passes over a flat front portion 118 of projection 54. Tool bit 109' will produce a cut on a wheel 115 corresponding to such flat portion. When corner 80 reaches the end of such flat portion, corner 80 will be forced down a sloped side 119 of projection 54 thereby producing a corresponding slope 120 on grinding wheel 115, spring 91 of arm 60 maintaining guide 76 in intimate contact with template 53 at all times. To reproduce sloped side 121 of projection 54, lever 63 is rotated in a counterclockwise direction which forces guide 76 to retrace the path just taken and then corner 79 will be forced down slope 121 thereby producing a corresponding slope 122 on wheel 115. The tool bit 109 dresses the wheel on the opposite side of grinding wheel 115. Bearings 42 and 43 provide relatively frictionless bearing support for bar 34 and block 27, thereby also insuring long life and optimum accuracy in such bearing.

From the foregoing description it is clearly apparent to those skilled in the art that there is here provided a grinding wheel dresser that quickly and accurately shapes a grinding wheel to any desired contour, the contour of such grinding wheel having sides disposed at 90 de-

grees or less from the face of such wheel. The tool bits 109 and 109' may be conveniently set to the desired distance from the face of tool holder 96 by means of a suitable gage and when once set will accurately dress any number of grinding wheels to the exact contour of template 53. It will also be appreciated that the grinding wheel dresser herein described is of sturdy construction yet light in weight enabling the operator to readily mount such dresser on any machine for dressing of the grinding wheel plate. The contour of the grinding wheel can be readily changed to any desired shape by merely replacing template 53 with one having the desired contour.

I claim:

1. A grinding wheel dresser for a machine tool having a grinding wheel, said grinding wheel dresser comprising, a bracket, said bracket having a pair of opposed upstanding arms arranged to support a shaft, a block member slidably mounted on said shaft, a tool holder slidably mounted in said block member for transverse movement with respect to said shaft, a cover plate secured on top of said bracket arms, a lever-like member pivotally mounted on said cover plate, means connecting said lever-like member with said tool holder, said tool holder arranged to be simultaneously moved in a transverse or longitudinal direction with respect to said shaft by said lever-like member, a template secured to said bracket, guide means associated with said tool holder and arranged to contact said template, and resilient means maintaining said guide means in intimate contact with said template, said template governing the movement of said tool holder whereby the contour of said template is reproduced on the grinding wheel.

2. A grinding wheel dresser for a machine tool having a grinding wheel, said grinding wheel dresser comprising, a bracket, a shaft rigidly mounted in said bracket, a block member slidably mounted on said shaft, a tool holder slidably mounted in said block member for transverse movement with respect to said shaft, a lever pivotally mounted on said bracket, said lever having an arm disposed beyond the pivot point of said lever, said arm being provided with an elongated recess therein, and a pin connecting said lever with said tool holder, said elongated recess accommodating one end of said pin whereby rotation of said lever moves said tool holder in any desired direction in a horizontal plane.

3. A grinding wheel dresser for a machine tool having a grinding wheel, said grinding wheel dresser comprising, a bracket, a shaft rigidly mounted in said bracket, a block member slidably mounted on said shaft, a tool holder slidably mounted in said block member for transverse movement with respect to said shaft, a lever pivotally mounted on said bracket, said lever having an arm disposed beyond the pivot point of said lever, said arm having an axial recess therein communicating with a transverse elongated recess, a pin connecting said tool holder with said lever, one end of said pin being inserted in said elongated recess, a spring mounted within said axial recess, and means to govern the movement of said tool holder when said lever is rotated, said spring being arranged to maintain said tool holder against said governing means.

4. A grinding wheel dresser for a machine tool having a grinding wheel, said grinding wheel dresser comprising, a bracket, a shaft rigidly mounted in said bracket, a block member slid-

ably mounted on said shaft, a tool holder slidably mounted in said block member for transverse movement with respect to said shaft, a lever pivotally mounted on said bracket, said lever having an arm disposed beyond the pivot point of said lever, said arm having an axial recess therein communicating with a transverse elongated recess, a pin connecting said tool holder with said lever, one end of said pin being inserted in said elongated recess, a spring mounted within said axial recess, a template secured to said bracket, and a guide member mounted on said pin, said guide member being disposed opposite said template, said template

determining the path of movement of said tool holder when said lever is rotated, said spring arranged to maintain said guide member against said template.
